ELECTRIC LAMP BRACKET

Filed June 4, 1929

Paul Ceasar Inventor

By his Attorney

Ivan E. A. Koenigsberg

UNITED STATES PATENT OFFICE

PAUL CEASAR, OF NEW YORK, N. Y.

ELECTRIC-LAMP BRACKET

Application filed June 4, 1929. Serial No. 368,309.

This invention relates to improvements in electric lamp brackets or supports for industrial purposes. More particularly this invention relates to a generally improved lamp bracket for supporting one or more electric lamps for use on serving machines and like machinery where it is necessary that the lamp or lamps be supported close to the work, yet in a position which does not interfere therewith, and whereby the lamps may be quickly adjusted for the purpose of efficient illumination.

The object of the invention is therefore to provide a lamp bracket adapted to support one or more standard electric lamps in a manner to provide rigid support, extreme adjustability and so arranged that the lamp cord does not become tangled with the bracket or unduly twisted no matter how the lamps are adjusted.

The invention is embodied in a lamp bracket having a clamping ring base support and above the latter there is provided interconnected brackets or supporting members permitting the lamp carried thereby to be adjusted practically universally in all directions with respect to the main supporting member.

The invention is illustrated in the accompanying drawing in elevation, partly perspective and with parts broken away.

Referring to the accompanying drawing, the reference numeral 1 denotes a main support in the form of a ring adapted to be firmly clamped to the frame of a sewing machine, for instance, by means of a bolt and nut as at 2. The dotted line 3 inside the ring represents the member to which the ring is clamped.

The ring 1 carries at the top a leg member 40 comprising two substantially symmetrical pieces 5 and 6 which are pivoted together at 7. The lower piece 5 is pivoted to the ring at 8. The axis of the pivot 8 being at right angles to the axis of the ring and the axis 45 of the pivot 7.

The upper leg piece 6 supports two symmetrical U-shaped lamp socket supports 9 and 10 which are pivoted to each other at the co-axial pivots 11 and 12, the pivot 12 also serving to pivot the two supports to the leg

piece 6. At the pivot 11 the U-shaped supports carry a plug bracket 13 which carries a standard push plug socket 14 adapted to receive the prongs of a standard push plug 15 at the end of the supply cable 16.

The drawing shows the one U-shaped support 10 moved on the pivots 11 and 12 out of alignment with the other support 9. Each support carries a nipple 17 to which is secured a standard electric lamp switch socket 18, 19. 20 indicates the lamps, parts of which are broken away.

The pivots which serve to connect the several parts may be of any usual friction type, or as shown at 7 and 11 wing bolts may be used for clamping adjacent parts in fixed adjusted position.

Each U-support 9 and 10 has a hole 21 permitting passage of the wire cables 22, 22 from the socket 14 to the lamp sockets 18 and 19.

From the drawing and the foregoing description it will be seen that the entire bracket is adjustable horizontally on the pivot 8, and the lamps are individually adjustable horizontally on the pivots 11 and 12.

The entire upper structure is adjustable vertically on the pivot 7 and the socket support 13, by reason of the pivot 11, is free to adjust itself and the socket 14 with respect to the cable 16 to allow for twists in the latter.

Again, by reason of the manner in which the cables 22 are mounted through the U-supports, each lamp may be adjusted horizontally without fear of pulling and twisting the cables.

The several parts of the device are duplicates and the entire structure may therefore be made at very little cost and at the same time very substantial to permit adjustments and long use.

While the invention is disclosed in its preferred form, nevertheless I wish it understood that I reserve the right to make such alterations and changes therein as fall within the scope of the appended claims.

I claim:

1. A lamp bracket comprising a main clamping ring, two pivotally connected opposed horizontally disposed symmetrical U-

- shaped lamp socket supports, means for supporting the latter on said ring to permit horizontal and vertical adjustment of said supports with respect to the ring, a push plug socket carried by said supports in rotatable relation thereto, means for supporting lamp sockets on said support and cables passing from said lamp sockets to the said push plug socket in fixed relation to the said supports.
- 5 2. A lamp bracket comprising a main supporting member, two lamp socket supports pivoted to each other and to the said support in individually horizontally adjustable relation and in horizontal and vertical adjustable relation to the said main supporting member, an upright supporting member pivoted on the said two supports, a push plug socket carried by said upright member, electric lamp sockets mounted on said supports and cables passing from said lamp sockets to the said push plug socket through holes in the said socket supports.
- 10 3. A lamp bracket comprising a main clamping member, a jointed upright support pivoted thereon at the top thereof, two lamp socket supporting brackets pivoted to said jointed member and to each other, the pivots of the said two brackets being co-axial 15 with the pivot between the main clamping member and the jointed support, electric lamp sockets mounted on the said two supporting brackets and means supported on the latter for supplying current to the said lamp 20 sockets.
- 35 4. A lamp bracket comprising a main clamping ring, two pivotally connected oppositely disposed horizontally placed symmetrical U-shaped lamp socket supports, a jointed member for mounting the two socket 25 supports on the main clamping ring, a push plug socket mounted on the said two socket supports in pivoted relation thereto and spaced a distance above the same, lamp 30 sockets on the same two supports and a cable passing from the push plug socket to each of the lamp sockets through a hole in each of the 35 said two supports.
